US00D879724S

(12) **United States Design Patent** (10) **Patent No.:** **US D879,724 S**
(45) **Date of Patent:** **** Mar. 31, 2020**

(54) **CONTACT WAFER**

- (71) Applicant: **Samtec, Inc.**, New Albany, IN (US)
(72) Inventors: **Jonathan E. Buck**, New Albany, IN (US); **John A. Mongold**, New Albany, IN (US)
(73) Assignee: **SAMTEC, INC.**, New Albany, IN (US)
(***) Term: **15 Years**
(21) Appl. No.: **29/647,260**
(22) Filed: **May 11, 2018**

(57) **CLAIM**

The ornamental design for a contact wafer, as shown and described.

DESCRIPTION

FIG. 1 is a top, front, and right side perspective view of a contact wafer showing our new design;

FIG. 2 is a top, back, and left side perspective view thereof;

FIG. 3 is a left side elevation view thereof;

FIG. 4 is a right side elevation view thereof;

FIG. 5 is a front elevation view thereof;

FIG. 6 is a back elevation view thereof;

FIG. 7 is a top plan view thereof; and,

FIG. 8 is a bottom plan view thereof.

1 Claim, 6 Drawing Sheets
